UNITED STATES PATENT OFFICE.

CHARLES J. BAILEY, OF NEWTON, MASSACHUSETTS.

DESIGN FOR A MASSAGE-ROLLER.

SPECIFICATION forming part of Design No. 35,655, dated February 4, 1902.

Application filed November 29, 1901. Serial No. 84,150. Term of patent 14 years.

To all whom it may concern:

Be it known that I, CHARLES J. BAILEY, a citizen of the United States, residing at Newton, in the county of Middlesex and State of Massachusetts, have invented and produced a new and original Design for a Massage-Roller, of which the following is a specification, reference being had to the accompanying drawings, forming a part hereof.

Figure 1 is a perspective view of the design for a massage-roller, and Fig. 2 is a side view thereof.

As shown in the drawings, the leading or material feature of my design consists of a cylindrical body A, provided externally with

a series of short hollow cylinders a, arranged about the periphery of the roller and extending therefrom.

Having described my design, what I claim as new, and desire to secure by Letters Patent, is—

The design for a massage-roller as herein shown and described.

In testimony whereof I have signed my name to this specification in the presence of two subscribing witnesses.

CHARLES J. BAILEY.
